[57]**CLAIM**

The ornamental design for combined bobbin with thermal transfer film, as shown and described.

DESCRIPTION

FIG. 1 is a perspective view of the combined bobbin with thermal transfer film of the present invention;

FIG. 2 is a front elevational view of the combined bobbin with thermal transfer film of FIG. 1 depicted in a fully loaded condition;

FIG. 3 is a view identical to FIG. 2 but indicating section lines thereon;

FIG. 4 is a rear view of the fully loaded combined bobbin with thermal transfer film;

FIG. 5 is a left side view of the fully loaded combined bobbin with thermal transfer film;

FIG. 6 is a right side view of the fully loaded combined bobbin with thermal transfer film;

FIG. 7 is a sectional view taken along lines 7—7 of FIG. 3; and,

FIG. 8 is a sectional view taken along lines 8—8 of FIG. 3.
